UNITED STATES PATENT OFFICE

THOMAS R. HAYTON, OF APPLETON, WISCONSIN, ASSIGNOR TO HAYTON PUMP & BLOWER COMPANY, OF APPLETON, WISCONSIN, A CORPORATION OF WISCONSIN

HYDROVACUUM PUMP

Application filed July 17, 1929. Serial No. 378,900.

My invention relates to pumps and particularly to a novel construction adapted and for use as a liquid piston vacuum pump or as a centrifugal pump when operated reversely.

An object of my invention is to provide a self priming pump that will operate efficiently either on air or water or a mixture thereof, the result being secured without the use 10 of any valves or moving parts other than the impeller.

The invention will be more readily understood by reference to the accompanying drawings, in which

15 Fig. 1 is a view partly in elevation and partly in section on the line 1—1 of Fig. 3;

Fig. 2 is a similar view on the line 2—2 of Fig. 4;

Fig. 3 is a transverse vertical sectional view;

Fig. 4 is a sectional view on the line 4—4 of Fig. 1;

Fig. 5 is a side elevation of one-half of the casing; and

25 Fig. 6 is a fragmentary sectional view on the line 6—6 of Fig. 1.

In the drawings, it will be seen that I provide a casing composed of two duplicate halves divided on the center line and joined 30 by means of bolts 10. Housings 11 are provided for roller bearings to support the drive shaft 12.

The impeller, later to be described, is secured to the shaft in the usual manner.

35 Glands or bushings 13 serve to prevent the escape of fluid around the shaft 12.

As each half of the casing is identical with the other I will specifically describe but one thereof. It will be noted that in the description, the construction and operation is 40 described in contemplation of the use of the pump as a vacuum pump. Of course for reverse operation the device will operate as a centrifugal pump and the designations for 45 the inlet and outlet will be reversed.

The casing is provided with an inlet 14 that is tangential to an annular concentric passage 15 of generally rectangular cross section as shown in Figs. 3 and 4. The wall 50 16 that defines the inner limit of the passage

15 is in the form of an eccentric rib, the inner periphery of which serves to define an inner eccentric chamber 17 having an entrance port 18. One-half of the rib 16 is cast on each of the sections or halves of the 55 casing and the impeller operates between the faces of the ribs. However, for convenience I have referred to the two ribs as a single rib.

At a point adjacent to the port 18, I mount 60 a deflector 19, constructed in two halves, as best shown in Fig. 6, and secured to the casing wall by means of screws 20. This deflector, the cross sectional shape of which is well shown in Fig. 6, serves to shut off the 65 passage 19 except for an area substantially equal to the area of the outer vanes on the impeller. The lower edge 21 of the deflector is arcuate or inclined, and is positioned to act as a means for deflecting the fluids into 70 the entrance port 18 and into the eccentric passage.

The outlet passage 22 is at the center of the casing, the passage being divided as shown in Fig. 4 so that the discharge is from 75 both sides of the impeller.

The impeller consists of a single casting, the hub 23 of which is mounted on the shaft 12. The inner vanes 24 are integral with the hub and project across the space at the inner part of the casing. At the outer ends the vanes 24 are integral with a solid web 25 that fits neatly between the faces of the ribs 16 on the two halves of the casing.

At the periphery of the impeller, I provide the vanes 26, integral with the web, the vanes being substantially smaller in area than the transverse area of the concentric passage 15. It will be noted that the vanes or blades 26 are arranged at an angle to radial lines and that this results in positioning the blades that are effective at the inlet in a position at an acute angle to the tangential axis of the inlet. This results in the formation of effective scoops and requires less lateral deflection of the incoming stream of air.

With the parts assembled, as shown, the operation is as follows:

Having placed a quantity of water within 100

the casing, the impeller is rotated in a clockwise direction.

The action of the blades or vanes 26 on the water in the concentric passage induces a high velocity, around the annular space. Water is continuously being supplied to the said annular space from the inside by being forced centrifugally through the narrow space between the edges of the rib 16 and the web 25 of the impeller, and that water is sprayed or broken up by the rapidly moving vanes and mixed with the incoming air. The whole body of water and air is thrown toward the outer wall of the annular passage and strikes the inclined surface 21 of the deflector at high speed. All the water and air in the passage, except that between the adjacent vanes is thrown into the port 18 and begins its travel around the eccentric passage 17. Due to the velocity and centrifugal force the air is squeezed out of the water and being of less mass than the water is forced between the vanes 24 toward the center. The converging wall presses the body of water between the vanes toward the center, forming in effect a liquid piston. As stated, the escape of water from the center chamber serves to constantly replenish the supply in the outer passage.

30 The great advantage in a pump of this character is that it is self priming and will operate to pump either liquid or air or intermittently either one or the other. The velocity imparted to the fluid column in the outer concentric passage insures an efficient compressing action in the eccentric passage. The extent of compression, or the degree of vacuum that may be secured is somewhat dependent upon the speed of rotation of the impeller, and this may be selected as desired.

40 While I have shown the pump as constructed in halves and prefer to so build it, it is obvious that it may be modified in this and other particulars without departure from the spirit of my invention.

I claim:

1. In a pump the combination of a casing providing an inlet and an outlet, means providing a concentric passage in communication with the inlet, means providing an eccentric passage having communication with the outlet, a deflector for partially closing said concentric passage at one point and for diverting a fluid into said eccentric passage, and an impeller having vanes operating in both said passages.

2. In combination, a casing having a concentric annular passage and an inlet tangential thereto, a deflector located in and restricting the area of the passage at a point adjacent to the inlet, an eccentric passage centrally within said first passage said deflector acting to divert fluids from the first into the second passage, means providing a

concentric outlet, and an impeller having vanes operating in both said passages.

3. In a pump the combination of a casing providing an inlet and an outlet, means providing a concentric passage in communication with the inlet, means providing an eccentric passage having communication with the outlet, a deflector for partially closing said concentric passage at one point and for diverting a fluid into said eccentric passage, and an impeller having vanes operating in both said passages, the vanes operating in the concentric passage being in the form of spaced-apart blades, each blade being arranged at an angle to a radial line from the axis of the impeller.

4. In combination, a casing having a concentric annular passage and an inlet tangential thereto, a deflector located in and restricting the area of the passage at a point adjacent to the inlet, an eccentric passage centrally within said first passage, said deflector acting to divert fluids from the first into the second passage, means providing a concentric outlet, and an impeller having vanes operating in both said passages, the vanes operating in the concentric passage being arranged at an angle to a radial line from the center of the impeller, the angle of the blades being such that the blades effective at the tangential inlet are disposed at an acute angle to the tangential axis of the inlet passage.

In testimony whereof I have affixed my signature.

THOMAS R. HAYTON.
